Primary Examiner — Paula Allen Greene(74) *Attorney, Agent, or Firm* — Tucker Ellis LLP(57) **CLAIM**

The ornamental design for headphone ear cup supports as shown and described.

DESCRIPTION

FIG. 1 is a front perspective view of headphone ear cup supports.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines show portions of the design that form no part of the claimed design.

1 Claim, 7 Drawing Sheets# US D1,113,811 S
